UNITED STATES PATENT OFFICE.

PLATO G. EMERY, OF CHICAGO, ILLINOIS.

VESTIBULE-CURTAIN FOR RAILWAY-CARS.

1,221,982.

Specification of Letters Patent. Patented Apr. 10, 1917.

Application filed September 22, 1914. Serial No. 862,898.

To all whom it may concern:

Be it known that I, PLATO G. EMERY, a citizen of the United States, residing in Chicago, in the county of Cook and State of Illinois, have invented a new and useful Improvement in Vestibule-Curtains for Railway-Cars, of which the following is a specification.

This invention relates to improvements in 10 vestibule curtains for railway cars.

An object of the invention is to provide an automatic uncoupling handle having a vestibule curtain so arranged that it will yield under excessive pull on the handle.

15 Other objects of the invention are to provide an automatic uncoupling handle of the type above indicated in which the use of springs is eliminated, and so constructed that it may be readily set and reset.

20 The invention furthermore consists in the improvements in the parts and devices and in the novel combinations of the parts and devices herein shown, described or claimed.

25 As is well known, vestibule curtains are secured to the vestibules of railway cars and are mounted on spring rollers, the curtains being pulled over the vestibule diaphragm and held on the adjacent ends of the vestibules of adjoining cars. In practice, it has 30 been found that a great many curtains are torn when the cars are separated because of the fact that the train men frequently neglect to uncouple the curtains before uncoupling the cars. In my invention, I provide 35 automatic means which will permit the curtain to be uncoupled under excessive pull, that is, when the cars are uncoupled, thereby preventing tearing of the curtains.

40 In the drawing forming a part of this specification, Figure 1 is a horizontal, sectional view showing portions of adjacent vestibules of two cars coupled together and showing also my improvements in connection therewith. Fig. 2 is a side elevation 45 and part sectional view of the improved automatic uncoupling handle, and showing in dotted lines the manner in which the handle is released or uncoupled. Figs. 3 and 4 are sectional views taken substantially on the 50 line 3—3 and 4—4 respectively of Fig. 2.

In said drawing, the vestibule curtain 10 is shown as mounted on a spring-actuated roller 11, the curtain having secured to the free edge thereof a handle designated generally by the reference A which is adapted 55 to be hooked over a catch 12 on a vestibule

adjacent to that on which the curtain is mounted, as shown in Fig. 1.

My improved handle, as shown, comprises two horizontally extending brackets 13 and 14 secured in any suitable manner to the free edge of the curtain, each of said brackets having mounted therein, a pivoted member 15. The upper member 15 is provided with an elongated socket 16 at its free end and the lower member 15 is provided with a similar socket 17 but of shorter length. These sockets 16 and 17, under normal conditions, will be in alinement with each other and will be so held by means of a piece of wood, stiff wire or other suitable substance 18 which is seated in the sockets 16 and 17 and extends past the ends thereof. This element 18 will be formed short enough so that it can be pushed up into 75 the socket 16 to thereby permit the two pivoted members 15 to be brought into alinement, after which the element 18 will fall under the influence of gravity into the socket 17. The length of the element 18 and 80 the socket 17 will be so proportioned that when the former falls into the socket 17, it will extend into both sockets 16 and 17.

In operation, the piece of wood or wire 18 will prevent the members 15 from swinging 85 about their pivots under normal conditions, but under excessive pull, the piece of wood or wire will bend, break or pull out, as indicated in dotted lines in Fig. 2 and will thereby permit the separation of the ends 90 of the two members 15 and automatically release or uncouple the handle.

From the foregoing description, it will be seen that the handle provided does not employ springs, which are more or less objectionable; any convenient piece of wood or wire may be used to hold the pivoted members 15 in alinement; the handle may be locked or set without difficulty and there are no undesirable projections or sharp 100 points which are likely to tear the clothing of persons passing through the vestibule.

I am aware that various modifications and changes may be made in the details of construction and arrangement of parts without departing from the spirit of the invention and all such changes and modifications are contemplated as come within the scope of the claims appended hereto.

I claim:

1. The combination of a curtain mounted 110 on the spring-actuated roller, of a handle

applied to the free edge of said curtain, said handle including a pivoted member having a socket therein adjacent to and in alinement with another socket of the handle and an element extending between said sockets preventing said pivoted member from swinging under normal pulls on the handle but adapted to yield and permit said member to swing under excessive pull on the handle, substantially as specified.

2. A device of the character described including, in combination: a vestibule curtain mounted on a spring-actuated roller; and a handle applied to the free edge of said curtain, said handle including two pivoted members having alined sockets at their free ends and an element within said sockets for preventing said pivoted members from swinging under normal pulls on the handle but adapted to yield and permit said members to swing and separate under excessive pull on the handle, substantially as specified.

3. A device of the character described including, in combination: a vestibule curtain mounted on a spring actuated roller; and a handle applied to the free edge of said curtain, said handle including a pivoted member and an element extending from the free end of said member engaging a part of the handle and preventing said member from movement under normal pulls but permitting said pivoted member to swing under excessive pull, substantially as specified.

4. A device of the character described including, in combination: a vestibule curtain mounted on a spring actuated roller; and a

handle applied to the free edge of said curtain, said handle including two separable members and means connecting their free ends to retain the curtain in open position under normal pull and permitting the release and separation of said members under excessive pull on the handle, substantially as specified.

5. A device of the character described including, in combination: a vestibule curtain mounted on a spring actuated roller; and a handle applied to the free edge of said curtain, said handle including movable members separable to permit release of the curtain, adjacent edges of said members being connected in sufficient security to withstand normal pulls on the handle and permitting separation of said members under excessive pull on the handle, substantially as specified.

6. A device of the character described including, in combination: a vestibule curtain mounted on a spring actuated roller; and a handle applied to the free edge of said curtain, said handle including two pivotal members and destructible means for holding said pivotal members in alinement in operative position under normal pulls on said handle, excessive pull on the handle destroying said means to permit release of said curtain, substantially as specified.

Signed this 19 day of November 1913 in the presence of two subscribing witnesses.

PLATO G. EMERY.
